UNITED STATES PATENT OFFICE.

WALTER T. WOODS, OF LONG BEACH, CALIFORNIA, ASSIGNOR TO U. S. TOOL COMPANY, OF LONG BEACH, CALIFORNIA, A CORPORATION OF CALIFORNIA.

MOUNTING FOR CUTTERS OF ROTARY WELL-DRILLING DISK BITS.

Application filed October 24, 1927. Serial No. 228,206.

This invention relates to the rotary well drilling bit of the type employed in the hydraulic rotary system of drilling wells. The disk bits employed in the hydraulic 5 rotary system of drilling wells have a tendency to lose one, or more, of the rotary cutters for the bit during drilling operations, unless the disk cutters are very securely mounted upon the bit body. An object 10 of the present invention is to provide an effective mounting for the disk cutters of the bit which will substantially reduce the danger of the cutters from being lost from the bit.

15 Various further objects and advantages of the invention will be apparent from the description of the preferred form, for example the disk bit embodying the invention. For this purpose reference is made to the 20 accompanying drawings in which one form, for example, of a disk bit embodying the invention, is shown.

In the drawings:

Fig. 1 is a vertical elevation of the preferred form of the well drilling bit.

Fig. 2 is an enlarged elevation at right angles to Fig. 1 of the lower portion of the bit.

Fig. 3 is an enlarged fragmentary view of 30 one of the disk cutters mounting means and a portion of the bit body or leg.

Fig. 4 is an end view of the mounting means.

Referring to the drawings, the well bit 35 there illustrated comprises an elongated body 1, having an enlargement 2 near its upper end and terminating in a tapered pin 3, by means of which the bit may be attached to a stand and drill pipe and rotated during 40 the drilling operations. The body 1 is provided with opposed legs 4 extending below the major portion of the body, the legs 4 being bent forwardly in the direction of rotation of the bit and preferably parallel, 45 as more clearly indicated in Fig. 2.

Each leg serves to support or mount a disk cutter 5. The cutters are supported on the inner sides of the legs so that they are disposed between the legs, and the legs are 50 sufficiently spaced apart so that there is provided between the cutters a substantial space through which the mud or detritus cut by the bit may pass. There is provided an axial opening 7 through the body for con-

vveying flushing fluid from the supporting 55 drilling pipe and discharge the same into the space between the legs, where it may admix with the detritus and aid in disintegrating and forming a mud fluid with the same.

60 Each of the disks 5 is mounted upon its supporting leg in a similar manner and, hence, only one of the mountings will be described. The mountings include a pin 10, part of which is inserted in the legs 4 and the other part extending outwardly from the legs. The latter part 12 is screw threaded and the inner part 11 of the pin is provided with a head 13. The leg 4 has an opening therein 14, fitting the portion 11 of the pin 10 and an enlarged opening 15 for receiving the head 13 of the pin 10. There is also provided a radial extension 16 of the opening 15 which receives a pin 17 in the head of the pin 10 for locking the 75 pin against rotation.

On the inner side of the leg 4 there is provided a combined washer and load transferring member 18 which is threaded to the portion 12 of the pin and is fitted in a recess 19 in the inner face of the leg 4, said load transferring member 18 is in turn recessed, as indicated at 20, to receive and fit the end of a bushing 21 which has a bearing portion 22 mounting a disk cutter 5. The bushing 21 also has a head 23 adapted to engage the cutter 5 to hold the same on the bushing. The pin 10 is threaded to the bushing 21. The pin 10 is also provided with an opening 24 for receiving a cotter pin and this pin 90 passes through one of a pair of diagonal notches 26 in the head of the bushing. A number of pairs of such diagonally oppositely placed notches are provided in the head of the bushing in order that the cotter pin 25 may be inserted in various desired positions.

100 By the mounting thus described the load on the disk cutters 5 is transferred first to the bushing 21 and said bushing in turn transfers the load to the load transferring member or washer 18, which in turn transfers the load to the leg 4. In this way most of the load on the pin 10 is removed. An important feature of the invention is the 105 use of the bushing 21 fitting in a recess in a washer 19 so that the bushing 21 is held for engagement with the leg 4. By this

construction the tendency of the end of the bushing to work into the leg, experienced in certain prior mountings, is eliminated and the wear is received by the washer 18 which 5 may be made of harder material than the leg 4 and which may also be readily replaced.

While the particular form of the invention herein described is well adapted to accomplish the objects, purposes and advantages 10 of the invention, it is understood that various modifications, changes and substitutions may be made without departing from the invention, and the invention includes all such modifications, changes and substitutions 15 as come within the scope of the appended claims.

I claim:

1. A rotary well drilling bit comprising a body, an opening through the body, a pin 20 extending through said opening, a bushing mounted upon said pin, a disk cutter carried by said bushing, a washer between said disk cutter and body, said washer having a recess therein fitting the engaging end of the bush- 25 ing.

2. A rotary well drilling bit comprising a body having an opening therethrough, a pin 30 extending through said opening, a bushing mounted on said pin and provided with a head, a disk cutter revolvably mounted upon said bushing, a washer between said disc cutter and the body, said bushing having its end engaging said washer and fitted into a recess in said washer.

3. A rotary well drilling bit comprising a body, a pin supported by the body, a bushing mounted upon the pin, a disk cutter supported by the bushing, a washer between the disk cutter and body, said washer being dis- 35 posed within a recess in said body so as to transfer part of the load from the disk cutter 40 to the body, thereby reducing the load upon

the pin, the bushing having one end fitted in a recess in said washer.

4. A rotary disk cutter comprising a body, 45 an opening through the body, a pin extending through said opening, a bushing mounted upon said pin, a disk cutter carried by said bushing, a washer between said disk cutter and body, said washer having a recess 50 therein fitting the engaging end of the bushing, and means for locking the pin against rotation, with respect to the body, and means for locking the bushing from rotating with respect to said pin.

5. A rotary disk cutter comprising a body having an opening therethrough, a pin extending through said opening, a bushing mounted on said pin and provided with a head, a disc cutter revolvably mounted upon said bushing, a washer between said disk cutter and the body, said bushing having its end engaging said washer and fitted into a recess in said washer, means for locking the pin against rotation, with respect to the 65 body, and means for locking the bushing from rotating with respect to said pin.

6. A rotary disk cutter comprising a body, a pin supported by the body, a bushing mounted upon the pin, a disk cutter supported by the bushing, a washer between the disk cutter and body, said washer being already disposed within a recess in said body so as to transfer part of the load from the disk cutter to the body, thereby reducing the load upon the pin, the bushing having one end fitted in a recess in said washer, means for locking the pin against rotation, with respect to the body, and means for locking the bushing from rotating with respect to said pin.

Signed at Los Angeles, Calif., this 18th day of Oct. 1927.

WALTER T. WOODS.
